US00D767548S

(12) **United States Design Patent** (10) **Patent No.:** **US D767,548 S**
(45) **Date of Patent:** **** Sep. 27, 2016**

(54) **NETWORKING DEVICE**

(71) Applicant: **Cisco Technology, Inc.**, San Jose, CA (US)

(72) Inventors: **Ian Matthew Snyder**, San Francisco, CA (US); **Morgan Davis Teachworth**, Campbell, CA (US); **Benjamin Arthur Calderon**, San Francisco, CA (US); **Sanjit Zubin Biswas**, San Francisco, CA (US)

(73) Assignee: **Cisco Technology, Inc.**, San Jose, CA (US)

(**) Term: **15 Years**

(21) Appl. No.: **29/542,001**

(22) Filed: **Oct. 9, 2015**

Related U.S. Application Data

(63) Continuation of application No. 29/475,982, filed on Dec. 10, 2013, now Pat. No. Des. 744,464.

(57) **CLAIM**

The ornamental design for a networking device, as shown and described.

DESCRIPTION

FIG. 1 is a front perspective view of the networking device; FIG. 2 is a rear perspective view of the networking device; FIG. 3 is a top plan view of the networking device; FIG. 4 is a bottom plan view of the networking device; FIG. 5 is a front elevation view of the networking device; FIG. 6 is a rear elevation view of the networking device; FIG. 7 is a side elevation view of the networking device; and, FIG. 8 is a side elevation view the networking device. Any portions shown using dashed lines are for illustrative purposes only and form no part of the claimed design.

1 Claim, 6 Drawing Sheets
